UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 6, 1924. Serial No. 690,934.

My invention relates to railway traffic controlling apparatus, and particularly to apparatus of the type comprising train carried governing means controlled by energy received from the trackway. More particularly, my invention relates to the trackway portion of such apparatus.

I will describe one form of trackway apparatus embodying my invention, and will then point out the novel features thereof in claims.

The accompanying drawing is a diagrammatic view showing one form of trackway apparatus embodying my invention.

Referring to this drawing, the reference characters 1 and 1^a designate the track rails of a railway over which traffic normally moves in the direction indicated by the arrow. These rails are divided, by means of insulated joints 2, into a plurality of successive track sections A—B, B—C, C—D, D—E, E—F, etc. Each such track section is provided with a track battery designated by the reference character Q with an exponent corresponding to the location and connected across the rails adjacent the exit end of the section. A resistance 16 is interposed between each track battery Q and one rail 1^a of the corresponding section in the usual manner.

Each track section is also provided with a track relay designated by the reference character R with an appropriate exponent and connected across the rails adjacent the entrance end of the corresponding section. Each track relay R is responsive to current supplied thereto from the track battery Q located at the opposite end of the corresponding section.

Traffic over the stretch of track shown in the drawing is controlled by wayside signals designated by the reference characters S with suitable exponents and located at intervals along the trackway. Each of the signals S may be of any suitable form and as here shown is of the semaphore type, and each such signal is capable of giving a "stop" and a "proceed" indication.

Associated with each of the track relays except relays R^c and R^f is an auxiliary relay designated by the reference character

G with a suitable distinguishing exponent.

Signals S^c and S^d are controlled over a circuit which may be traced from one terminal O of a suitable source of energy not shown in the drawing, through front contact 17 of track relay R^f, wire 18, front contact 19 of track relay R^e, wire 20, winding of relay G^e, wire 21, front contact 22 of track relay R^d, wire 23, winding of relay G^d, wire 24, operating mechanism of signal S^d, wire 25, front contact 26 of track relay R^c, wire 27, operating mechanism of signal S^c, wire 28, back contact 29 of track relay R^b, and wires 30 and X back to the other terminal P of the energy source. It is therefore plain that if relays R^c, R^d, R^e and R^f are energized, the relay R^b is de-energized, the operating circuit for signals S^c and S^d is closed, thus causing these signals to display proceed indications. At the same time relays G^d and G^e are energized, it being noted that the latter relays are included in series with the operating mechanism of signals S^c and S^d. The circuit just traced is provided with a branch which passes from wire 25, through back contact 26 of track relay R^c, wire 31, to common wire X. It is therefore clear that when relay R^c is de-energized signal S^c is de-energized but signal S^d still indicates proceed and relays G^d and G^e are still energized over back contact 26 of relay R^c. Another branch is provided which may be traced from wire 21, through back contact 22 of track relay R^d, and wire 32 to wire X. If relay R^d is de-energized, therefore, and relays R^e and R^f are both energized, signals S^c and S^d will both indicate stop, relay G^d will be de-energized, and relay G^e will be energized.

The control of signals S^a and S^f and relays G^a and G^f will be readily understood from the foregoing.

Each track section is provided with a track transformed designated by the reference character K with an exponent corresponding to the location and having its secondary winding 14 interposed between the associated track battery Q and one rail of the corresponding section. An impedance 100 15 is interposed between the secondary winding 14 of each track transformer K

and one rail 1 of the corresponding section in the usual manner.

Associated with each track section is a line transformer designated by the reference character T with a distinguishing exponent. The primary winding 8 of each such line transformer is constantly supplied with alternating current from some suitable source of energy such as an alternator H over line wires 3 and 3a.

Track transformer K^c is at times energized over a circuit which passes from secondary 9 of line transformer T^c, through wire 33, primary winding 13 of track transformer K^c, wire 34, front contact 35 of track relay R^c, and wire 36 back to secondary 9 of line transformer T^c. Track section B—C is therefore supplied with alternating track circuit current by track transformer K^c when relay R^c is energized. The supply of alternating track circuit current to section E—F is controlled by track relay R^f in the same manner as that just described for section B—C.

Track transformer K^d is provided with a circuit which passes from secondary 9 of line transformer T^d, through wire 37, back contact 38 of auxiliary relay G^d, wire 39, primary 13 of track transformer K^d, wire 40, back contact 41 or relay G^d and wires 42 and 43 back to secondary 9 of line transformer T^d. This circuit is closed only when relay G^d is de-energized, under which condition section C—D is supplied with alternating track circuit current of one relative polarity, which I will term "reverse relative polarity". When relay G^d is energized current flows from secondary 9 of transformer T^d through wire 37, front contact 41 of relay G^d, wire 40, primary 13 of transformer K^d, wire 39, front contact 38 of relay G^d, and wire 43 back to secondary 9 of transformer T^d. When this circuit is closed alternating track circuit current of the other relative polarity, which I will hereinafter term "normal relative polarity", is supplied to section C—D from transformer K^d. The partial sections immediately to the left of point A and immediately to the right of point F are supplied with alternating track circuit current in the same manner as section C—D.

When relay G^e is energized current flows from secondary 9 of transformer T^e, through wire 44, primary 13 of transformer K^e, wire 45, front contact 46 of relay G^e, and wire 47 back to secondary 9 of transformer T^e. When this circuit is closed alternating track circuit current of normal relative polarity is supplied to section D—E by transformer K^e. Transformer K^b is controlled in the same manner as transformer K^e.

Means are also provided for supplying the rails of each section in parallel with an

alternating current which I will hereinafter term a "local" current. For this purpose I provide each section with an impedance 4 connected across the rails adjacent the entrance end of the section, and a similar impedance 7 connected across the rails adjacent the exit end of the section. In addition to impedances 4 and 7 the section to the right of point F and section C—D are each provided also with two impedances 5 and 6 connected across the rails at an intermediate point in the section. Local current is supplied by local transformers designated by the reference characters L with appropriate exponents. The primary 10 of each local transformer L is constantly supplied with alternating current from the secondary 9 of an associated line transformer T. Section B—C is constantly supplied with local current from a circuit which may be traced from secondary 12 of local transformer L^c, through wire 49, impedance 4 in section B—C, through both rails of the section in parallel to impedance 7, and wire 50 back to secondary 12 of transformer L^c. Section E—F is provided with a local circuit similar to that just described for section B—C.

Section C—D is provided with one local circuit which passes from secondary 11 of local transformer L^c, through wire 51, impedance 4 in section C—D, through both rails of the section in parallel to impedance 5, and wire 52 back to secondary 11 of transformer L^c. Another local circuit is provided for this section over which current flows from secondary 12 of transformer L^d, through wire 53, impedance 6 in section C—D, through both rails of the section in parallel to impedance 7, wire 54, front contact 55 of relay G^d, and wire 56 back to secondary 12 of transformer L^d. It is therefore obvious that section C—D is constantly supplied with local current between impedances 4 and 5, and is supplied with local current between impedances 6 and 7 when relay G^d is energized but not when the relay is de-energized. The local circuits for the partial section to the left of point A and the partial section to the right of point F are similar to the local circuits for section C—D. The local circuit for section D—E may be traced from the secondary 11 of transformer L^d, through wire 57, impedance 4 in section D—E, through both rails of the section in parallel to impedance 7, through wire 58, front contact 59 of relay G^e, and wire 60 back to secondary 11 of transformer L^d. Section D—E is therefore supplied with local current only when relay G^e is energized. The supply of local current to section A—B is controlled by relay G^b in the same manner as the supply of local current to section D—E by relay G^e.

Before explaining the operation of this apparatus as a whole it should be pointed

out that the trackway apparatus herein shown and described is suitable for co-operation with train carried governing means in the following manner: When a train occupies a portion of track which is supplied with local current and with track circuit current of normal relative polarity, a proceed indication is received on the train; when the train occupies a stretch of track which is supplied with local current and with track circuit current the relative polarity of either of which currents is reversed, a caution indication is received on the train; and when the train is on a portion of track from which the supply of either local current or track circuit current is discontinued, a stop indication is received on the train.

As shown in the drawing the parts of the apparatus all occupy their normal positions, that is, the positions corresponding to an unoccupied condition on the track. In this condition each of the track relays R is energized, each of the signals S indicates stop, and each of the relays G is de-energized.

I will now assume that a train moving in the direction of the arrow passes through the stretch of track shown in the drawing.

As the train enters section B—C, the de-energization of track relay R^B closes the circuit for signals S^C and S^D and these signals therefore indicate proceed. At the same time, of course, relays G^D and G^E are energized. Section B—C is supplied constantly with local current, and relay R^C being energized, this section is also supplied with track circuit current of normal relative polarity. The train therefore receives a proceed indication as it proceeds through section B—C.

When the train passes signal S^C , the de-energization of relay R^C closes the branch through wire 31 for signal S^D and relays G^D and G^E , but signal S^C now indicates stop. Since relay G^D is energized, track circuit current of normal relative polarity is supplied to section C—D and local current is supplied to this section between impedances 6 and 7 over front contact 55 of relay G^D . The train therefore receives a proceed indication throughout section C—D. As the train enters section D—E relay R^D is de-energized, thus interrupting the circuit for relay G^D and signal S^D . Signal S^D therefore displays a stop indication. Relay G^E , however, is still energized over back contact 22 of relay R^D . Track circuit current of normal relative polarity is therefore supplied to section D—E by transformer K^E and local current is supplied to this section by secondary 11 of transformer L^P . The train therefore receives a proceed indication throughout section D—E. Section E—F is also supplied with track circuit current of normal relative polarity and with local current, and the train therefore receives a

proceed indication throughout section E—F.

I will now assume that a train, moving in the direction of the arrow, proceeds into section C—D and stops, and that a following train enters section B—C. Due to the presence of the first train in section C—D, relay R^C is de-energized and signal S^C is at stop. The circuit for the primary of transformer K^C is therefore open, and the second train, being deprived of track circuit current, receives a stop indication throughout section B—C. If the second train enters the occupied section, track circuit current from transformer K^D will be shunted from such second train by the wheels and axles of the train already occupying section C—D and the following train will continue to receive a stop indication.

If a train occupies section D—E, signals S^C and S^D will indicate stop, and relay G^D will be de-energized. Relay R^D will be de-energized and relay R^C energized. Under these conditions section B—C is supplied with track circuit current of normal relative polarity and also with local current. Track circuit current of reverse relative polarity is supplied to section C—D throughout its length and local current is supplied to section C—D between impedances 4 and 5 but not between impedances 6 and 7. If, now a following train proceeds past point B, such train will receive a proceed indication between points B and C, a caution indication between point C and impedance 5 in section C—D, but will receive a stop indication between impedance 6 and point D. The train will also receive a stop indication, as previously explained, if it proceeds into the occupied section D—E.

If section E—F is occupied, relays R^E and G^E , will both be de-energized. The supply of train governing current to sections B—C and C—D is the same as explained in connection with a train occupying section D—E but the supply of both local current and track circuit current to section D—E is now interrupted. A train moving toward the right receives a proceed indication throughout section B—C, a caution indication between point C and impedance 5 in section C—D, and a stop indication from impedance 6 in section C—D as far as the obstruction in section E—F.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track, a sig-

nal for said stretch, a relay, means controlled by said relay for supplying said stretch with periodic energy for the control of train-carried governing means, and integral means for controlling said signal and said relay.

2. Railway traffic controlling apparatus comprising a stretch of railway track, a signal for said stretch, a relay, means controlled by said relay for supplying said stretch with periodic energy for the control of train-carried governing means, and integral means for controlling said signal and said relay in accordance with traffic conditions.

3. Railway traffic controlling apparatus comprising a stretch of railway track, a signal for said stretch capable of displaying at least two different indications, a relay, integral means for controlling said relay and said signal in accordance with traffic conditions, and means controlled by said relay for supplying said stretch with periodic energy for the control of train-carried governing means when the signal is displaying one indication but not when the signal displays a different indication.

4. Railway traffic controlling apparatus comprising a stretch of railway track, a signal for said stretch, a relay, an operating circuit for said signal including a winding of said relay, and means controlled by said relay for supplying energy to said stretch for the control of train-carried governing means.

5. Railway traffic controlling apparatus comprising a stretch of railway track, a signal for said stretch, a relay, an operating circuit for said signal including a winding of said relay and controlled by traffic conditions, and means controlled by said relay for supplying current to said stretch for the control of train-carried governing means.

6. Railway traffic controlling apparatus comprising a stretch of railway track, a signal for said stretch, a relay, an operating circuit for said signal including a winding of said relay and controlled by traffic conditions in rear of said stretch, and means controlled by said relay for supplying current to said stretch.

7. Railway traffic controlling apparatus comprising a stretch of railway track, a signal for said stretch, a relay, an operating circuit for said signal including a winding of said relay and controlled by traffic conditions in advance of said stretch, and means controlled by said relay for supplying current to said stretch.

8. Railway traffic controlling apparatus comprising a stretch of railway track, a signal for said stretch, a relay, an operating circuit for said signal including a winding of said relay, and a local circuit for said stretch controlled by said relay for the control of train-carried governing means.

9. Railway traffic controlling apparatus

comprising a stretch of railway track, a signal for said stretch, a relay, an operating circuit for said signal including a winding of said relay, and means controlled by said relay for supplying track circuit current to said stretch for the control of train-carried governing means.

10. In a railway traffic controlling system comprising a stretch of railway track and train carried governing means responsive to current flowing in said stretch, the combination with the afore-mentioned instrumentalities of a trackway signal, a relay, an operating circuit for said signal including a winding of said relay and controlled by traffic conditions, and means controlled by said relay for supplying such current to said stretch.

11. Railway traffic controlling apparatus comprising a stretch of railway track, a signal for said stretch, a relay, an operating circuit for said signal including a winding of said relay, and means controlled by said relay for supplying said stretch with track circuit current of one relative polarity or the other.

12. Railway traffic controlling apparatus comprising a stretch of railway track, a signal for said stretch, a relay, an operating circuit for said signal including a winding of said relay, and means controlled by said relay for supplying said stretch with track circuit current of one relative polarity or the other, and for at times also supplying said stretch with local current.

13. Railway traffic controlling apparatus comprising a stretch of railway track, a signal for said stretch, a relay, an operating circuit for said signal including a winding of said relay, and means controlled by said relay for at times supplying said stretch with local current and with track circuit current of one relative polarity and for at other times supplying the stretch only with track circuit current of the other relative polarity.

14. Railway traffic controlling apparatus comprising a stretch of railway track, a signal for said stretch, a relay, an operating circuit for said signal including a winding of said relay, and means controlled by said relay for at times supplying said stretch with local current and with track circuit current and for at other times supplying said stretch only with track circuit current.

15. Railway traffic controlling apparatus comprising a stretch of railway track, a signal for said stretch, a relay, an operating circuit for said signal including a winding of said relay, and means controlled by said relay for supplying said stretch with track circuit current throughout the length of the stretch and for at times supplying local current to a portion only of said stretch.

16. Railway traffic controlling apparatus comprising a stretch of railway track, a sig-

nal for said stretch, a relay, an operating circuit for said signal including a winding of said relay, and means controlled by said relay for supplying said stretch with track circuit current of one relative polarity or the other throughout the length of the stretch and for at times supplying local current to a portion only of said stretch.

17. Railway traffic controlling apparatus comprising a stretch of railway track, a signal for said stretch normally displaying a stop indication, an operating circuit effective when energized to cause said signal to display a proceed indication, a relay included in said circuit, means for energizing said circuit when a train approaches the signal, and means controlled by said relay for supplying current to said stretch.

18. Railway traffic controlling apparatus comprising a stretch of railway track, a signal for said stretch arranged to at times display a stop indication, an operating circuit effective when energized to cause said signal to display a proceed indication, a relay included in said circuit, means for energizing said circuit when a train approaches the signal, means for subsequently maintaining said circuit in its energized condition until the train passes the signal, and means controlled by said relay for supplying periodic energy to the trackway in rear of said signal.

19. Railway traffic controlling apparatus comprising a stretch of railway track, a signal for said stretch, an operating circuit for said signal arranged to be energized when a train approaches said signal, two relays each having a winding included in said circuit, means controlled by one such relay for supplying current to the trackway in rear of said signal, and means controlled by the other relay for supplying current to the trackway in advance of the signal.

20. Railway traffic controlling apparatus comprising a stretch of railway track, a signal for said stretch, an operating circuit for said signal arranged to be energized when a train approaches said signal, two relays each having a winding included in said circuit, and means controlled by said two relays for supplying current to the trackway.

21. Railway traffic controlling apparatus comprising a stretch of railway track, a signal for said stretch, an operating circuit for said signal arranged to be energized when a train approaches said signal, two relays each having a winding included in said circuit, and means controlled by said two relays for supplying alternating current to the trackway.

22. Railway traffic controlling apparatus comprising a stretch of railway track, a signal for said stretch, an operating circuit for said signal arranged to be energized when a train approaches said signal, two relays each

having a winding included in said circuit, and means controlled by said two relays for supplying the trackway with alternating local current.

23. Railway traffic controlling apparatus comprising a stretch of railway track, a signal for said stretch, an operating circuit for said signal arranged to be energized when a train approaches said signal, two relays each having a winding included in said circuit, means controlled by one said relay for supplying alternating current to a portion of the trackway and means controlled by the other said relay for supplying alternating current to a different portion of the trackway.

24. Railway traffic controlling apparatus comprising a stretch of railway track, a signal for said stretch, an operating circuit for said signal arranged to be energized when a train approaches said signal, two relays each having a winding included in said circuit, means controlled by one said relay for supplying a portion of the trackway with track circuit current and with local current, and means controlled by the other said relay for supplying track circuit current and local current to a different portion of said trackway.

25. Railway traffic controlling apparatus comprising a section of railway track, a source of direct current connected with the rails of said section, a track relay connected with the rails of said section and responsive to current from said source, a trackway signal, an operating circuit for said signal controlled in part by said track relay, an auxiliary relay having a winding included in said circuit, means for energizing said circuit when a train approaches said signal, and means controlled by said auxiliary relay for supplying said section with alternating current.

26. Railway traffic controlling apparatus comprising a stretch of railway track, a signal for said stretch, a relay, an electrical circuit including the operating mechanism of said signal and a winding of said relay in series, means for closing said circuit when a train approaches said signal and means controlled by said relay for supplying said stretch with alternating current for the control of train-carried governing means.

27. Railway traffic controlling apparatus comprising a stretch of railway track, a signal for said stretch normally indicating stop, a relay, an operating circuit arranged to be closed when a train approaches said signal and including a winding of said relay, and means controlled by said relay for supplying periodic energy to said stretch for the control of train-carried governing means.

28. In combination, a stretch of railway track, a signal for said stretch normally indicating stop but arranged to indicate pro-

ceed when a train approaches the signal, and means for supplying said section with track circuit current for the control of train-carried governing means when said signal indicates proceed but for at times discontinuing such supply when said signal indicates stop.

29. In combination, a stretch of track, a direct current track circuit for said stretch, a signal normally indicating stop, means controlled in part by said track circuit for causing said signal to display a proceed indication when a train approaches said signal, and means controlled in accordance with the indication displayed by said signal for supplying alternating current to said stretch for the control of train-carried governing means.

30. In combination, a stretch of track, a direct current track circuit for said stretch, a signal normally indicating stop, means controlled in part by said track circuit for causing said signal to display a proceed indication when a train approaches said signal, and means for supplying alternating current of one relative polarity or the other to said stretch in accordance with the indication displayed by said signal.

31. In combination, a stretch of track, a direct current track circuit for said stretch, a signal normally indicating stop, means controlled in part by said track circuit for causing said signal to display a proceed indication when a train approaches said signal, and means for applying across the rails of said stretch an alternating electromotive force of one relative polarity, or the other according as said signal displays a stop or a proceed indication.

32. In combination, a section of railway

track, a source of local current normally disconnected from said section, and means controlled by a train approaching said section and also by a train occupying said section for supplying the two rails in multiple of said section with local current from said source. 40 45

33. In combination, a section of railway track, a source of local current normally disconnected from said section, and means responsive to traffic conditions in advance and controlled by a train approaching said section and also by a train occupying said section for supplying the two rails of said section in multiple with local current from said source. 50

34. In combination, a stretch of railway track, a signal for said stretch normally indicating stop, an operating circuit for causing said signal to indicate proceed and arranged to be closed when a train approaches the signal, and means associated with said circuit for controlling the supply of local and track circuit current to said stretch. 55 60

35. In combination, a section of railway track, a normally open circuit for supplying local current to the two rails of said section in parallel, and means controlled by a train approaching said section for completing said circuit. 65

36. In combination, a stretch of railway track, a source of alternating current normally disconnected from said stretch, and means controlled by traffic conditions in advance for supplying the rails of the stretch with traffic controlling current of one relative polarity or the other from said source when a train approaches said stretch. 70 75

In testimony whereof I affix my signature.

RONALD A. McCANN.
